UNITED STATES PATENT OFFICE.

PETER W. N. KING, OF FORT MYERS, FLORIDA.

DESIGN FOR A TOY FLOAT.

46,680.

Specification for Design.

Patented Nov. 24, 1914.

Application filed September 14, 1914. Serial No. 861,727. Term of patent 3½ years.

To all whom it may concern:

Be it known that I, PETER WALTER NICKOLUS KING, a citizen of the United States, residing at Fort Myers, in the county of Lee and State of Florida, have invented a new, original, and ornamental Design for Toy Floats, of which the following is a specification, reference being had to the accompanying drawing, forming part thereof.

The figure is a perspective view of a toy float, showing my new design.

I claim:

The ornamental design for a toy float, as shown.

PETER W. N. KING.

Witnesses:

F. B. TIPPINS,
B. S. MITCHELL.
